UNITED STATES PATENT OFFICE.

MARSHEL HAMPTON, OF BOWERS, INDIANA.

FARM-SLED.

SPECIFICATION forming part of Letters Patent No. 625,500, dated May 23, 1899.

Application filed February 28, 1898, Serial No. 672,065. (No model.)

To all whom it may concern:

Be it known that I, MARSHEL HAMPTON, a citizen of the United States, residing at Bowers, in the county of Montgomery and State of Indiana, have invented certain new and useful Improvements in Farm-Sled Runners; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a side elevation of the sled. Fig. 2 is a side view, partly in section.

My invention relates to sled-runners; and it consists in the construction and novel combination of parts, as will be hereinafter fully described, and particularly pointed out in the claim.

Referring by letters to the accompanying drawings, A designates a sled-runner which is applicable to farm-sleds provided with wooden soles.

B is one of the improved braces, which is made of wood, having a tenon at the upper end and also having a notch cut at obtuse angles in lower end, which is joined to front end of runner A.

C is a wrought-iron plate curved to fit the contour of the wooden runner and secured to the runner rave and brace by three bolts.

D is a short cast-iron shoe having bolt-holes cast tapering, which receive two bolts, the heads of which rest in countersinks, so that the bottom of the metal shoe presents a smooth surface to the snow or mud, as the case may be.

T is wooden sole, which also forms a part 40 of the runner and is fastened to the sled by means of two wooden pins H H.

O O designate the joints in the runner.

S S are the bolts used in connecting the different parts of the runner. 45

The strain comes on the brace and iron plate which serves as a support to the front joint in the runner, and the short cast-iron shoe is also a protection to the iron plate and a support to the joints, being curved to fit the 50 contour of the runner at front end.

I am aware that it is not new to provide a metallic shoe. I am also aware that similar shoes have been provided which may engage the runner its entire length, and therefore do 55 not claim such devices broadly.

Having thus fully described my invention, what I claim as new, and desire to secure by Letters Patent of the United States, is—

A sled-runner consisting of the runner 60 proper, a brace connecting the front end of the runner with the rave and forming the nose of said runner, a curved strap-iron on the front side of the brace connecting the rave and the front end of the runner, a curved shoe upon 65 the front of the strap-iron and a sole upon the runner extending from the rear end of the shoe to the rear end of the runner, the several parts being secured together in the manner shown and described. 70

In witness whereof I have hereunto set my hand this 25th day of February, 1898.

MARSHEL HAMPTON.
